C. M. BALDWIN.

COLLAPSIBLE COT.

APPLICATION FILED SEPT. 27, 1916.

1,261,893.

Patented Apr. 9, 1918.

UNITED STATES PATENT OFFICE.

CHARLES M. BALDWIN, OF HUDSON FALLS, NEW YORK.

COLLAPSIBLE COT.

1,261,893.

Specification of Letters Patent.

Patented Apr. 9, 1918.

Application filed September 27, 1916. Serial No. 122,433.

To all whom it may concern:

Be it known that I, CHARLES M. BALDWIN, a citizen of the United States, and resident of Hudson Falls, in the county of Washington and State of New York, have invented certain new and useful Improvements in Collapsible Cots, of which the following is a specification.

The present invention relates to beds and 10 has particular reference to new and useful improvements in collapsible cots, the device having for its primary object the provision of a novel and improved type of collapsible cot particularly adapted for Army use.

15 The primary object of my invention is to provide a collapsible cot having a novel construction, whereby the same may be quickly and easily set-up for use or knocked down and packed away for traveling.

20 Another object of my invention is to provide a cot of the class described which is simple in construction, strong and durable, cheap to manufacture and will occupy a minimum amount of space when folded for 25 transportation from place to place.

A further object of my invention is to provide a cot of the class described having a novel form of supporting body and suspending means therefor whereby when folded 30 the parts thereof will be received within the body, the latter forming a wrapper or protector therefor.

Other objects and advantages to be derived from the use of my improved 35 collapsible cot will appear from the following detailed description and the claim, taken with an inspection of the accompanying drawing, in which:

Figure 1 is a top plan view of a cot embodying the improvements of my invention, the same being shown in set-up position;

Fig. 2 is a longitudinal sectional view of the same;

Fig. 3 is an enlarged fragmental perspective view of two of the side sections and connecting means therefor;

Fig. 4 is an enlarged fragmental end view of the leg bracing means; and

Fig. 5 is an enlarged transverse sectional 50 view taken on line 5—5 of Fig. 1.

Referring more particularly to the drawing, wherein similar characters of reference designate like and corresponding parts throughout the various views, A and B designate side frames of my improved cot, the 55 same being composed of angle-irons formed

in a plurality of sections 10 and 11. The adjacent ends of the side sections 10 and 11 are connected in a manner best shown in Fig. 3.

Referring specifically to Fig. 3 the adjoining ends of side sections are shown, said ends being enlarged as at 12 and 13, the ends 12 being formed with a tongue 14, the free end of the tongue having a head 15 thereon. A recess 16 is formed in the enlargement 13, 60 said recess 16 conforming in shape to the contour of the head 15 whereby to readily receive the same. An enlargement 17 is provided on the intermediate section of each side frame, the same being formed to receive the threaded end 18 of a supporting 70 leg 19.

End frames C and D are provided, the same being formed of angle-irons and connected at 20 and 21 to the side frames A and B by 75 connecting members similar to those shown in Fig. 3. A plurality of braces, one of which is shown in Fig. 4 and designated 22 are provided, the brace 22 as shown in Fig. 4 being pivoted at 23 to the end frame member 80 C, the end frame member C being shown, the free end of said brace being provided with a recess 24 to engage a pin 25 carried by one of the legs 26. The upper end of the leg 26 is connected at 27 with the end frame 85 member, the end frame member C being shown, which the same is intended to support, this connection being identical with the connecting means for the side frames and end sections.

Upon reference to Fig. 1 it will be noted 90 that the cot of my invention tapers throughout its length, the head of the same being wider than the foot. Of course, I do not desire to be limited to this shape of cot in view of the fact that the same may be readily 95 changed by increasing the length of the end frame C.

The supporting body of the cot is preferably formed of canvas, the same being designated E. The side margins of the supporting body E are folded as at 30 and stitched to reinforce the same. A plurality of eyelets are provided in the supporting body E adjacent the folded portions thereof, said eyelets serving to receive a cord or 100 twine lacing 32, the latter passing through openings 33 formed in the side frames A and B. Relatively large eyelets 34 are provided in the foot 10 of the body E to receive straps 36, said straps embracing the 105 end frame member C.

The head end of the body E is preferably

curved and provided with a plurality of eyelets 38 to receive the free ends of suspending springs 39, the free ends of the latter being connected to the openings 40 formed in the 5 end frame member D. A curved bar 42 serves to reinforce the head end of the supporting body E.

To set up my improved cot B the side sections 10 and 11 are engaged as shown in 10 Fig. 1, the lacing 32 being loosened. The straps 36 and springs 39 may be permanently attached to the supporting body E since the latter will readily flex under tension when setting-up the cot. The free ends 15 of the endmost sections of the side frames are engaged in the end frames C and D as indicated at 20 and 21 in Fig. 1. The supporting frame of the cot is now in set-up position. The end legs 26 are inserted into 20 position and the bracing members 22 connected therewith. The intermediate supporting legs 19 may now be placed in the enlargement 17 and the lacing 32 tightened. The cot is now in condition for use and it 25 will be seen that owing to the curved arrangement of the head end of the same an even distribution of the strain is afforded.

It will be readily apparent to those skilled 30 in the art that when desired the cot of my invention may readily be folded, the sections thereof being rolled into the supporting body E. The size of the same when folded is such that it may readily be carried in the usual kit now in use in the Army.

35 From the above description taken in con-

nection with the accompanying drawing, it is thought that a clear and comprehensive understanding of the construction, operation and advantages of my invention may be had, and while I have shown and described 40 the device as embodying a specific structure, I desire that it be understood that such changes may be made in said structure as do not depart from the spirit and scope of the invention as claimed. 45

Having thus fully described my invention, what I claim as new and desire to secure by Letters Patent, is:—

In a knock-down cot, side rails comprising intermediate portions having the opposite 50 ends thereof recessed and the intermediate portions formed with recessed enlarged portions, end sections detachably engaged in the recessed ends of the intermediate sections, end rails movably engaged with the 55 opposite ends of said side rails, said side and one of the end rails having series of openings formed therein, a flexible body, means for adjustably connecting the sides of the body to the side rails, coiled springs engaged with the openings in said end bar and with the body, straps engaged with the remaining end bar and with the adjacent end of said body, and supporting legs secured to the side rails adjacent their opposite ends 60 and receivable in the recessed enlarged portions of the intermediate sections thereof.

In testimony whereof, I affix my signature hereto.

CHARLES M. BALDWIN.

Copies of this patent may be obtained for five cents each, by addressing the "Commissioner of Patents, Washington, D. C."
